DESIGN FOR A GAME APPARATUS

Bryant Wiest, Elizabethville, Pa.

Application May 31, 1938, Serial No. 77,467

Term of patent 14 years

To all whom it may concern:

Be it known that I, Bryant Wiest, a citizen of the United States residing in Elizabethville, county of Dauphin, and State of Pennsylvania, have invented a new, original, and ornamental Design for a Game Apparatus, of which the following is a specification, reference being had to the accompanying drawing, forming a part thereof, in which

Fig. 1 is a front elevation of the game apparatus showing my new design, and

Fig. 2 is a top plan view thereof.

In the said drawing the pointer and each of the smaller disks between the pointer and the largest disk are shown in arbitrarily selected relative positions on their common axis of rotation.

I claim:

The ornamental design for a game apparatus, substantially as shown and described.

BRYANT WIEST.
